(57) **CLAIM**

The ornamental design for a rocker switch bezel, as shown and described.

DESCRIPTION

FIG. 1. Top upper right perspective view of a rocker switch bezel incorporating my new design, and shows a typical switch case and rocker with which the bezel design might be used.

FIG. 2. Is a front elevational view thereof.

FIG. 3. Is a top plan view thereof.

FIG. 4. Is a left-hand side elevational view thereof; and, FIG. 5. Is right-hand side elevational view thereof.

No bottom view is shown as the bottom of the article would not readily appear, but would be obscured by the switch housing.

The broken line showing of the environment is for illustrative purposes only and forms no part of the claimed design.

The bottom view of the rocker switch bezel is not shown as it forms no part of the claimed design.
